SWEETENING HYDROCARBON OILS WITH AIR AND CAUSTIC SOLUTION CONTAINING LEAD, BISMUTH, OR THALLIUM

Louis D. Rampino, Concord, Calif., assignor to Tide-water Oil Company, San Francisco, Calif., a corporation of Delaware

Application January 30, 1957, Serial No. 637,316

23 Claims. (Cl. 196—29)

This invention relates to the sweetening of hydrocarbon liquids by the conversion of mercaptans, and to the suppression of peroxide and gum formation during such sweetening.

This application is a continuation-in-part of my applications Serial Number 472,048, filed November 30, 1954, and Serial Number 582,717, filed May 4, 1956, both consolidated herein without additional disclosure, both now abandoned.

In the refining of petroleum, special problems are presented by the presence of mercaptans. Hydrocarbon oils, especially cracked gasolines, nearly always contain small quantities of mercaptans, which have a disagreeable odor and other undesirable properties.

In petroleum refining, two general methods are used to reduce the mercaptan content of hydrocarbon oils. One of these methods is to extract the mercaptans with various alkaline solutions, and the other is to convert the mercaptans into more innocuous compounds which remain dissolved in the oil. In some operations, the major part of the mercaptans are extracted and the sweetening is completed by conversion of the remaining mercaptans.

A number of processes are available for the reduction of the mercaptan content of oils. The best known of these sweetening processes are: the doctor process; the alkaline hypochlorite process; copper sweetening; the solutizer process; and, more recently, the so-called "inhibitor sweetening" with phenylene diamine type inhibitor. However, each of these processes is subject to certain definite shortcomings. Thus, in the doctor process, in which a caustic-washed oil is agitated with a little sulfur and an aqueous alkaline solution of sodium plumbite, it is difficult to control accurately the required amount of elemental sulfur. If too much sulfur is added the excess remains in the oil and, if greater than about 10 parts per million, may render the gasoline corrosive. In addition, the free sulfur tends to react with disulfides formed during the processing to give polysulfides. The latter greatly reduces the susceptibility of the oils for tetraethyllead.

Treating with alkaline hypochlorite, while valuable for sweetening straight run gasolines, is little use on cracked petroleum products, primarily because the strong oxidizing effect of the hypochlorite tends to produce unstable color and gum-forming compounds. As in doctor sweetening, it is also difficult to gauge the amount of hypochlorite to be added due to the everchanging mercaptan content of the oils undergoing treatment. Copper sweetening is also little used since the slightest trace of excess copper in the oil will accelerate oxidation giving rise to gums.

The solutizer processes depend on the use of a substance termed "solutizer," to increase the solubility of unneutralized mercaptans in the caustic wash solutions. Substances such as alkyl phenols and sodium or potassium

2

salts of the lower molecular weight fatty acids are useful as solutizers. In addition to being expensive, these processes normally do not produce a "doctor sweet" product (mercaptan sulfur content of 0.0002 gm./100 cc. of distillate, or less) since they depend on extraction of the mercaptans which is never complete.

To a greater or lesser degree, all the aforementioned processes have an additional disadvantage of requiring extensive equipment for handling large volumes of treating agent. In some of these processes relatively expensive treating or revivifying agents are used, and occasionally large losses of these reagents are encountered. As a result, these processes are apt to be expensive, difficult to control and not always effective.

Recently, a process for sweetening certain hydrocarbon oils by means of oxygen dissolved in the oil in the presence of an oil-soluble N-alkyl derivative of paraphenylenediamine was developed. This process, often termed "inhibitor sweetening," due to use of a compound commonly employed to inhibit the oil against oxidation, has advantages over the sweetening processes just described since it is simply controlled, inexpensive, convenient and effective. However, a serious difficulty often encountered in inhibitor sweetening operations is the by-product formation of organic peroxides which in turn lead to increased gum formation and, in use, dirtier engines. As gum formation also tends to increase with increased boiling range, with inhibitor sweetening, it is often necessary to control gum formation by reducing the end distillation temperature of naphtha fractions to a lower degree than would otherwise be necessary. This latter procedure results in poor manufacturing economies by curtailing the effective use of the heavier refinery stocks.

The present invention is directed to a simple, effective and inexpensive process for sweetening hydrocarbon liquids which is not subject to the defects of the prior art, and which results in much lower gum formation and cleaner engines. Accordingly, one object of the present invention is to provide a process for rendering hydrocarbon liquids doctor-sweet without employing elemental sulfur and with a minimum formation of peroxides. Another object of the invention is to provide such a process that is easily controlled, inexpensive and rapidly carried out. Another object of the invention is to provide an improved sweetening process that may be carried out simultaneously with caustic washing of the hydrocarbon liquid. Another object of the invention is to provide a sweetening process in which the capacity of a caustic solution used to extract mercaptans is continuously renewed without the necessity of adding expensive revivifying agents. A still further object of the invention is to provide an improved sweetening process, involving inhibitor sweetening, in which both the consumption of inhibitor and the formation of peroxides and gums are reduced to a minimum. Another object is to provide a process for altering objectionable mercaptans in hydrocarbon liquids that is highly effective regardless of substantial variations in the mercaptan content.

Another object is to provide a process for sweetening hydrocarbon oils of higher boiling range that cannot be satisfactorily sweetened by conventional inhibitor sweetening.

Other objects and advantages of the present invention will be apparent from the following detailed description, from the specific examples enumerated herein, and from the drawing in which Figs. 1 and 2 are flow diagrams of two differing forms of a process for sweetening hydrocarbon oils embodying the invention.

In accordance with the first form of the invention to be discussed, mercaptans contained in hydrocarbon oils are caused to react with peroxides formed during inhibitor sweetening of the oils (or, if desired, by a direct addition of peroxides to the system), in the presence of aqueous caustic and small amounts of mercaptide-forming metals that easily undergo oxidation-reduction reactions. Such metals are known to include various forms of lead, bismuth, and thallium which apparently act as catalysts for the reaction, although the exact mechanism is not understood. An explanation presently advanced is that certain compounds of the metal are oxidized by the peroxides and the resulting compounds subsequently reduced by the mercaptans to compounds suitable for reacting with more peroxides. In effect the sweetening process becomes also a peroxide destroying process, resulting in lower gum formation and cleaner engines due to the lower peroxide content of the sweetened oil. As an example, excellent results are obtained with lead in the plumbous form. Due primarily to the low cost and ready availability of commercial doctor solution, this is the preferred source of plumbous lead. The term "doctor solution" is used in this specification, as is commonly employed in the petroleum art, to denote aqueous alkaline solutions of sodium plumbite (Na_2PbO_2).

In accordance with the second form of the invention to be discussed, a sour cracked hydrocarbon oil is inhibited with a hindered phenol type of inhibitor and also a phenylene diamine type of inhibitor and then contacted with aqueous caustic in the presence of air and a small amount of the aforementioned mercaptide-forming metals that easily undergo oxidation-reduction reactions and apparently act as catalysts for the reaction of mercaptans and peroxides formed during inhibitor sweetening of the oil. Hindered phenols found effective include 2,6-ditertiary butyl para cresol and 2,6-ditertiary butyl phenol. Other examples include 2,6-ditertiary amyl phenols and other 2,6-ditertiary alkyl phenols in which any or all of the remaining ring positions are substituted by alkyl groups. The hindered phenol prevents peroxide from being formed at too fast a rate. The ready availability of 2,6-ditertiary butyl para cresol makes this the preferred source of hindered phenol.

Also, in accordance with both forms of the invention, substantial amounts of the mercaptans are dissolved in the aqueous caustic as mercaptides and are thereupon converted to disulfides which are returned to the oil undergoing treatment. As a result, the caustic becomes to a large extent "revivified" and may again be used in the sweetening process without the necessity of expensive procedures or reagents normally required for regeneration. Although the chemical reactions involved in this revivification are not clearly understood, it is apparent that the metal catalysts used are highly effective in the aqueous phase to promote the reaction of peroxides with the mercaptides to form disulfides. The converted disulfides are then extracted from the caustic through contact with the hydrocarbon oil. In addition, a particular phenomenon of the present invention is a continuing, although lessened, catalytic effect produced by recirculating caustic that has once been used in the new sweetening process. This is entirely contrary to prior experience and indicates that the presence of catalyst in the treating tank alters the caustic in some way not understood, permitting the process to be successfully carried out without a continuous injection of catalyst. Generally, however, continuous injection of catalyst is preferred.

In practicing the first-mentioned form of the invention, it is desirable to first contact the mercaptan-containing oil with a phenylene diamine type inhibitor in the presence of air and aqueous caustic, as is customary in inhibitor sweetening processes. A minute amount of the metal catalyst is mixed with the oil either before, simultaneously, or preferably after contacting the oil with the

caustic. The mixture of the oil, caustic and catalyst is then allowed to stand for a sufficient time to permit the desired amount of conversion of mercaptans and peroxides, after which the separated oil is passed to storage or blended with other components to form a finished fuel. The revivified caustic settling from the mixture may then be recycled for further use in the sweetening process.

In determining particular metals useful as catalysts in the present invention, it appears that the metal should not only have different states of oxidation, but also should be capable of readily reacting with mercaptans contained in the hydrocarbon oils to form mercaptides. Moreover, the mercaptides formed should be easily oxidizable; otherwise the effect of catalysts, thought to result from the metal varying between its oxidized and reduced forms, cannot be achieved. Thus it is found that compounds of lead, bismuth and thallium will readily react with mercaptans to form mercaptides, with the hydrogen of the mercaptan (RSH) being replaced by the metal. Similarly, the mercaptides of these metals are readily oxidized. Forms of metals useful in carrying out the present invention are illustrated in the following examples:

EXAMPLE 1

- 25 A number of tests were conducted by shaking 25 cc. of spent caustic (10° Baumé) in a brown quart bottle with 500 cc. of caustic-washed, catalytically cracked naphtha having a boiling range of 95° F. to 268° F. The naphtha employed was derived primarily from California and Middle East crudes and had previously been inhibited with NN' disecbutyl paraphenylenediamine at the rate of 7.5 pounds per 1,000 barrels of naphtha. In each of the tests, metal in a form suitable as a catalyst was added to the caustic before shaking. After shaking, the bottle was capped with a slotted cork to allow access to air. The metals were added to the caustic as follows:
- (a) Blank, no metal added.
  - (b) 0.2 cc. of doctor solution having a concentration equal to 24 grams of PbO per liter of solution (4.8 mg. PbO).
  - (c) 7 mg. of solid PbO_2 (lead peroxide).
  - (d) 4.9 mg. PbO_2 heated to boiling with 4 cc. of 35° Baumé NaOH and diluted to 25 cc. with the spent caustic (sodium plumbate).
  - (e) 5.6 mg. PbO_2 heated with the spent caustic.
  - (f) 10.9 mg. of $\text{Bi}(\text{OH})_2\text{NO}_3$ (bismuth subnitrate) heated with 3 cc. of 35° Baumé NaOH and diluted to 25 cc. with the spent caustic.

50 The tendency of the added metals to prevent or reduce peroxide formation and consequent gum formation in sweetened gasolines is shown in Table A:

In the preparation of Table A, and subsequent tabulated data, the doctor test was conducted according to Federal Specification VV-L-791C, Method 520.2; per-

5

oxide numbers were determined by U. O. P. Method H-33-40; and blended copper dish gums by a modification of Federal Specification VV-L-791b, Method 330.1, in which the treated stock was blended in equal proportions with an acid treated solvent extract boiling between 190° and 270° F. Results obtained by said modified method are herein referred to as "blended copper dish gum."

EXAMPLE 2

The procedure of Example 1 was repeated using the same catalytically cracked stock. However, the metals added to the caustic were as follows:

- (g) Blank, no metal added.
- (h) 0.01 cc. of the doctor solution of Example 1.
- (i) 1 cc. of the sodium plumbate solution (d) of Example 1.
- (j) Solid Pb_2O_3 (lead sesquioxide) prepared by adding cumene hydroperoxide to 5 cc. of the doctor solution of Example 1, and filtering and water washing the precipitate.
- (k) 1 gram of $PbCO_3$ (lead carbonate).
- (l) Metaplumbic acid (H_2PbO_3) prepared by adding an excess of 6 N nitric acid to 2 grams of red lead (Pb_3O_4), and washing the precipitate with dilute nitric acid.

The results of these tests are set forth in Table B:

EXAMPLE 3

The procedure of Example 1 was again repeated with the following metals added to the caustic before shaking with the naphtha:

- (m) Blank, no metal added.
- (n) 13.1 mg. of bismuth trioxide (Bi_2O_3) heated with 3 cc. of 35° Baumé NaOH.
- (o) 13.1 mg. of bismuth tetroxide heated with 3 cc. of 35° Baumé NaOH.

The results of these tests appear in Table C.

EXAMPLE 4

To compare the effect of thallium compounds with lead compounds, under the procedure of Example 1, the following metals were added to 25 cc. of caustic before shaking with the naphtha:

- (p) Blank, no metal added.
- (q) 2.2 mg. of thallium in the form of thallous chloride, dissolved in the caustic.
- (r) 11.0 mg. of thallium in the form of thallous chloride, dissolved in the caustic.
- (s) 0.1 cc. of the doctor solution of Example 1 (equivalent to 2.2 mg. of Pb).
- (t) 0.5 cc. of the doctor solution of Example 1 (equivalent to 11.0 mg. of Pb).

The effect of thallium compounds in preventing peroxide formation in sweetened gasolines is shown in the following table:

Table D

3 DAYS AFTER SHAKING WITH CAUSTIC

Test Performed	Form and Amount of Metal Added				
	(p) No Metal	(q) Thallous Chloride (2.2 mg. Th)	(r) Thallous Chloride (11.0 mg. Th)	(s) Doctor Solution (2.2 mg. Pb)	(t) Doctor Solution (11.0 mg. Pb)
Grams mercaptans per 100 cc. of naphtha Peroxide No.-----	0.00035 0.58	0.00019 0.20	0.00026 0.29	0.00013 0.29	0.00022 0.39

9 DAYS AFTER SHAKING WITH CAUSTIC

Peroxide No.-----	0.45	0.11	0.11	0.11	0.23

The results set forth in Examples 1 to 4 show that both bismuth and thallium are effective in reducing peroxide formation, and that lead is effective in either the plumbous (Pb^{++}) or plumbic (Pb^{+++}) form.

In practicing the second-mentioned form of the invention, it is desirable to first add to the mercaptan-containing oil a hindered phenol type of inhibitor and also a phenylene diamine type inhibitor and then contact the inhibited oil with aqueous caustic in the presence of air. A minute amount of the metal catalyst is mixed with the dually inhibited oil either before, simultaneously, or preferably after contacting the oil with the caustic. The mixture of the oil, caustic and catalyst is then allowed to stand for a sufficient time to permit the desired amount of conversion of mercaptans and peroxides, after which the separated oil is passed to storage or blended with other components to form a finished fuel. The revivified caustic settling from the mixture may then be recycled for further use in the sweetening process. This form of the present invention is illustrated by the following examples:

EXAMPLE 5

A number of tests were conducted by shaking 35 cc. of 10° Baumé caustic in a brown quart bottle with 700 cc. of heavy thermally cracked naphtha having a boiling range of 206 to 390° F. The naphtha employed was derived primarily from California and Middle East crudes and had been previously inhibited with phenylene diamine inhibitor or with tertiary butyl para cresol inhibitor or both. In some of the tests plumbous lead, in the form of 0.15 cc. of doctor solution, was added to the caustic before shaking with gasoline. After shaking, the bottle was capped with a slotted cork to allow access to air. Changes in mercaptan sulfur, gum, and peroxide number were measured over a period of 7 day with results shown in Table E.

7

Mercaptan Sulfur of Caustic	0.0016	0.00016	0.0021	0.00088	
Peroxide No.	2.0	1.8	0.59	0.52	1.2
ASTM Gum	6.4	6.6	0.4	0.2	1.4
Blended Copper Dish Gum	181	176	78	31	82

The results in Table E show that the conventional inhibitor sweetening process produced a sweet product of too high gum content to be satisfactory and that even the addition of doctor solution to the caustic did not remedy this situation. Table E also shows that when gasoline is inhibited with only 2,6-ditertiary butyl para cresol sweetening time is too slow to be of practical value. Best results were obtained when the gasoline contained both inhibitors and when doctor solution was present in the caustic to speed up the rate of sweetening. Under these conditions product quality of the sweet gasoline was satisfactory.

It should be also noted that the concentration of mercaptans in the caustic layer was considerably lowered by the presence of doctor solution. It appears that one function of doctor solution is to accelerate the disappearance of mercaptans in the caustic and thereby accelerate the rate of gasoline sweetening by shifting the equilibrium of mercaptans between gasoline and caustic.

In the preparation of Table E, and subsequent tabulated data, peroxide number was determined by U. O. P. method H-33-40; and blended copper dish gum by a modification of Federal Specification VV-L-79 Lb., Method 330.1, in which the treated stock was blended in equal proportions with an acid-treated solvent extract boiling between 190° and 270° F. Results obtained by said modified method are herein referred to as "blended copper dish gum." Mercaptan sulfur was determined by the method given on page 618 of Ind. Eng. Chem. Anal., 13th ed., No. 9 (September 15, 1941). ASTM gum was measured by Method D381-52T.

EXAMPLE 6

The procedure of Example 5 was repeated using, however, a light catalytically cracked stock with a boiling range of 105° to 295° F. The naphtha, derived from cracking of a mixture containing primarily California and Middle East crudes, had been previously inhibited with phenylene diamine inhibitor or with 2,6-ditertiary butyl para cresol or both. In one case 2,6-ditertiary butyl phenol was substituted for the cresol.

Tests were conducted by shaking 700 cc. of inhibited gasoline in a brown quart bottle with 25 cc. of 10° Baumé caustic to which no doctor solution was added in some cases and 0.1 cc. of doctor solution was added to others. After shaking, the bottle was capped with a slotted cork to allow access to air. Blank experiments were also performed in which uninhibited gasoline was stored in absence and presence of 10° Baumé caustic. Changes in mercaptan sulfur, gums, and peroxide numbers were measured over a period of several days for each gasoline. Table F shows the results obtained with uninhibited gasoline.

8

Table F
SWEETENING OF UNINHIBITED LIGHT CATALYTIC NAPHTHA

25	Inhibitor Content	0	0
	Caustic	Absent	Present
	Mercaptan Sulfur at start, gms. per 100 cc.	0.0039	0.0039
	After 1 day	0.00365	0.0002
	After 2 days	0.00360	
	After 7 days	0.00346	
30	Copper dish gum: After 1 day	3	740

Table F shows that sweetening of uninhibited gasoline is impractical for the following reasons: in absence of caustic, sweetening time is extremely long; in presence of caustic, sweetening is accompanied by a large increase in gum.

Table G compares sweetening time, gum, and peroxide number of the same gasoline inhibited with different inhibitors and stored over caustic.

Table G
SWEETENING OF INHIBITED LIGHT CATALYTIC GASOLINE

45	Inhibitor, lbs./1,000 bbls:				
	Phenylene diamine	10	0	10	10
	2,6-Ditertiary Butyl para cresol	0	5	5	0
	2,6-Ditertiary Butyl phenol	0	0	0	5
50	Caustic	Present	Present	Present	Present
	Mercaptan Sulfur at Start, gms./100 cc.	0.0039	0.0039	0.0039	0.0039
	After 2 days	0.00086	0.0020	0.00083	0.00086
	After 4 days	0.00015	0.0015	0.00038	0.00022
	After 7 days		0.0010	(sour)	(sour)
55	Tests after 7 days—				
	Peroxide No.	0.38	0.12	0.22	0.25
	ASTM Gum	1	1	1	1
	Blended Cu Dish Gum	33	6	6	8

The results in Table G show that when gasoline is inhibited with only 2,6-ditertiary butyl para cresol, sweetening time is too slow to be of practical value. Gasoline inhibited with only phenylene diamine sweetens at the fastest rate but gives, with this type of gasoline, higher gum and peroxide number after sweetening.

Gasolines inhibited with both phenylene diamine and hindered phenols sweeten at an intermediate rate; gum and peroxide content of the sweet gasolines are considerably lower than in the case where no hindered phenol is present.

In accordance with the invention, advantage is taken of the product-improvement quality of the hindered phenol without the disadvantage of a decreased rate of sweetening. This involves having a small amount of doctor solution present in the caustic.

Table H shows the improvements obtained in both

speed of sweetening and in product quality when doctor solution is present in the caustic.

Table H
SWEETENING OF LIGHT CATALYTIC NAPHTHA:
EFFECT OF DOCTOR SOLUTION

Inhibitor, lbs./1,000 bbls.:					
Phenylene diamine	10	10	10	0	
2,6-difert. butyl para cresol	0	5	0	5	
2,6-difert. butyl phenol	0	0	5	0	10
Doctor Solution	Present	Present	Present	Present	
Mercaptan Sulfur at start, gms./100 cc.	0.0039	0.0039	0.0039	0.0039	
After 2 days	0.00013 (sweet)	0.00017 (sweet)	0.00015 (sweet)	0.00050 (sour)

Peroxide No.					15
ASTM Gum					
Blended Cu Dish Gum	10	4	3	4	

Comparison of Table G and Table H reveals that doctor solution greatly accelerates the rate of sweetening in all cases; the retarding effect of a hindered phenol is practically absent when phenylene diamine inhibitor is also present; and, in addition, peroxide number and copper dish gum of the sweet gasoline are markedly lower.

The first-mentioned form of the invention may be better understood by reference to Fig. 1 which illustrates, in diagrammatic form, apparatus suitable for carrying out the invention. "Sour" naphtha (i. e., naphtha containing objectionable amounts of mercaptans) which may be taken directly from the fractionating system of a cracking plant or from storage, and which previously may have received a light wash with caustic soda solution to remove traces of fatty acids, H_2S , and other substances more acidic than mercaptans, is fed to pump 2 through line 1 whence it is forced through line 3, mixing device 8 (including mixing orifices 8'), and line 4 to tank 9 and thence through line 10 to storage. Mixing in device 8 may advantageously be assisted by recycling through line 12 and recycle pump 13.

Prior to the entry of the naphtha stream into mixing device 8, a desired proportion of inhibitor is added as, for example, from tank 5 through valve 6 and proportioning pump 7. Oxygen to effect the reaction is preferably supplied, in the form of air or other gas containing free-oxygen, through line 11 after the introduction of the inhibitor in order that passage through the mixing device 8 may assist the solution of the oxygen in the naphtha. Simultaneously with the injection of inhibitor, the naphtha is preferably contacted with a quantity of aqueous caustic sufficient to dissolve the more soluble of the mercaptans in the caustic as mercaptides. After settling, the caustic in tank 9 (below level 18) may be returned to the process through line 14 by recycle pump 15. Spent caustic passed to the drain through valve 16 may be replaced by fresh caustic from tank 17, as needed.

According to the invention, a minute quantity of metal catalyst is admixed with the oil, either before, simultaneously, or preferably after contacting the oil with caustic. In the illustrated process, the desired proportion of catalyst is added from tank 20 through valve 21 and proportioning pump 22. The intermixed oil and caustic containing respectively inhibitor and catalyst in solution are then allowed to stand in tank 9 a sufficient time to permit the mercaptans contained in the oil to react by catalysis with the peroxides formed through addition of the oxygen. Because of a continuing catalytic effect (believed to result from oxidation-reduction reactions of the metal catalyst) sweetening of the naphtha, as evidenced by conversion of the mercaptans to disulfides, is achieved simultaneously with conversion of the peroxides to alcohols. Thus, in the practice of the invention, cracked naphthas which normally tend to form gums are simultaneously treated to reduce mercaptan content and gum formation.

After injection of the metal catalyst, the naphtha is

allowed to stand in time tank 9, or in other storage, for a period sufficient to permit the desired amount of conversion of mercaptans and peroxides, usually from 1 to 10 days. While the process is illustrated as continuous, in the sense that sweetened naphtha may be periodically withdrawn from tank 9, it will be understood that the treated fuel may be introduced into more than one time tank so as to obtain the benefits of longer periods of standing in contact with the caustic. Thus, when tank 9 is substantially full, the treated stock flowing through line 4 may be introduced into another time tank (not shown), and tank 9 isolated for a desired time by shutting valves 23, 24, and 25.

In the second-described form of the invention, shown in Fig. 2, the same general procedure is followed, except that prior to the entry of the naphtha stream into mixing device 8, a desired proportion of the two inhibitors phenylene diamine and a hindered phenol is added separately or as a mixture as, for example, from tanks 5 and 5' through valves 6 and 6' and proportioning pump 7. Oxygen to effect the reaction is again preferably supplied, in the form of air or other gas containing free-oxygen, through line 11 after the introduction of the inhibitor in order that passage through the mixing device 8 may assist the solution of the oxygen in the naphtha.

Where a heavy naphtha is to be sweetened, a light hydrocarbon or mixture of light hydrocarbons is injected to increase the vapor pressure to 5 to 6 lbs. prior to the entry of oxygen into the system. In this way explosion hazards are safely eliminated.

It may be advantageous to keep the gasoline moving while in contact with the caustic. This may be conveniently done by continuously withdrawing a portion of the gasoline in the time tank and injecting this into line 4 either before or after injection of the catalyst, as for example through valve 26, pump 27 and line 28 of Fig. 2.

Both forms of the invention are particularly adapted, though not restricted, to the treatment of naphthas containing relatively low (in the order of 0.01% of mercaptan sulfur) but objectionable amounts of mercaptans. Such naphthas may result from the cracking of low sulfur stocks, or they may result from the treatment of higher mercaptan content naphthas by any one of several mercaptan removal processes, such as extraction with caustic soda solution, with or without a so-called "solutizer."

The amount of catalyst required to sharply reduce gum formation is extremely small. For example, when using a commercial doctor solution containing approximately 15 grams PbO per liter of solution, from about 1.5 to 15 gallons of solution per 1000 barrels of oil has been found to be effective. Stated otherwise, a continuous injection of from about 0.00005 part to about 0.001 part by weight lead in the plumbous form per 100 parts of hydrocarbon oil will produce the desired result. On the other hand, too large an injection of lead, that is, more than about 0.003 part per 100, may unnecessarily retard the rate of sweetening. When using various forms of bismuth or thallium as the catalyst, similarly low amounts of catalyst appear satisfactory.

The following are examples of the practice of the first mentioned form of the invention according to the general procedure outlined in the drawing, and, with particular reference to lead, illustrate the effect of different concentrations of the catalyst metals.

EXAMPLE 7

A catalytically cracked naphtha, from the cracking of a mixture of gas oils derived primarily from California and Middle East crudes with a boiling range of 106° F. to 266° F., and having a mercaptan content (as sulfur) of 0.006 gram per 100 cc. of stock is processed as in the drawing. The sour naphtha is charged at a rate of 250 barrels per hour and injected with 19 pounds per hour of NN' disethyl butyl paraphenylenediamine inhibitor. A 2.9 percent solution of aqueous caustic soda from the time tank is

recycled with the charge at 60 barrels per hour. Air at the rate of 90 standard cubic feet per hour is then injected into the charge. After thorough mixing, catalyst in the form of doctor solution of a concentration of 9.25 grams PbO per liter of solution is injected at a rate of 1.4 gallons per hour (0.000135 percent Pb by weight). Tests on samples taken just before the treated naphtha enters the time tank, and at various periods after entering the tank, are set forth in Table I.

Table I

Data Collected	At Entrance To Time Tank	After 2 days in Time Tank	After 8 days in Time Tank
Grams mercaptans S per 100 cc. of naphtha.....	0.0012	Less than 0.0002	Less than 0.0002
Peroxide Number.....	0.45	0.13	0.06
Blended Copper Dish Gum.....	10	7	4
ASTM Gum.....	0.2	0.0	0.0

In Table I and subsequent tables, mercaptan sulfur is determined by the method set forth on page 618 of Ind. Eng. Chem. Analysis., 13th ed., No. 9 (September 15, 1941), and ASTM Gum by Method D381-52T.

Example 8

A catalytically cracked naphtha similar to that in Example 5 but having an initial mercaptan content (as sulfur) of 0.0068 gram per 100 cc. of naphtha is processed in the same manner as in Example 7, except the concentration of the doctor solution is increased to 14.3 grams of PbO per liter (0.00021 percent Pb by weight) and a 4.5 percent solution of caustic soda is employed. Samples are withdrawn from the time tank and tested as shown in Table J.

Table J

Data Collected	At Entrance To Time Tank	After 1 day in Time Tank	After 6 days in Time Tank
Grams Mercaptans S per 100 cc. of naphtha.....	0.00051	Less than 0.0002	Less than 0.00020
Peroxide Number.....	0.39	0.11	0.08
Blended Copper Dish Gum.....	7	3	0
ASTM Gum.....	0.4	0.2	0.2

EXAMPLE 9

The procedure of Example 7 is repeated on catalytically cracked naphtha, similar to that in Example 7, having an initial mercaptan content (as sulfur) of 0.0035 gram per cc. of naphtha with the following variations, the caustic being circulated is increased in concentration to a 6 percent solution, and the concentration of the doctor solution to 19.6 grams of PbO per liter (0.00029 percent Pb by weight). Tests on samples taken just before and at various periods after the naphtha entered the time tank produce the following results:

Table K

Data Collected	At Entrance To Time Tank	After 1 day in Time Tank	After 4 days in Time Tank
Grams Mercaptans S per 100 cc. of naphtha.....	0.00000	0.00070	Less than 0.00020
Peroxide Number.....	0.62	0.25	0.11
Blended Copper Dish Gum.....	9	5	2

The results of Examples 7, 8 and 9 demonstrate that an increase in the amount of metal present does not necessarily tend to further reduce peroxide and gum formation and, consequently, indicate the catalytic nature of the metal.

EXAMPLE 10

Prior to any injection of the catalyst metals of the invention, catalytically cracked naphtha (from a mixture of gas oils derived primarily from California and Middle

East crudes and having a mercaptan content (as sulfur) of from 0.005 to 0.007), is charged to the system shown in the drawing. The naphtha is then injected with inhibitor and air and mixed with caustic in the amounts and proportions set forth in Example 7. Mercaptan sulfur is determined in a series of tests on samples taken at the entrance to the time tank. Similarly, peroxide and gum formation is determined in another series of tests on samples of sweetened naphtha drawn from the time tank (approximately 2 days after entrance into the time tank). The entire procedure is then repeated with the additional injection of 1.42 gallons per hour of doctor solution (containing from 9.5 to 19 grams PbO per liter). A comparison of these series of tests is set forth below:

Table L

Data Collected	No Metal Injection	Doctor Solution Injected
Mercaptans S per 100 cc. of entering naphtha.....	0.002-0.0025	0.0005-0.001
Peroxide No. of sweetened naphtha.....	0.8-1.5	0.1-0.4
Blended Copper Dish Gums.....	20-40	0-8
ASTM Gums.....	0.4-1	0-0.4

These results indicate clearly that not only are the gasolines sweetened with a minimum formation of peroxides and a consequent reduction in the formation of gums, but also that the gasolines are sweetened more rapidly than is possible merely with inhibitor sweetening.

The following example, in contrast to Examples 7 to 10, illustrates sweetening of naphtha over longer periods of time under batch process conditions.

EXAMPLE 11

A catalytically cracked naphtha, similar to that in Example 7 but having a boiling range of 104° F. to 269° F., and having a mercaptan content (as sulfur) of 0.0029 gram per 100 cc. of stock is charged at a rate of 250 barrels per hour and injected with 1.9 pounds per hour of NN' disecbutyl paraphenylenediamine inhibitor. A 6.5 percent solution of aqueous caustic soda is mixed with the charge at 60 barrels per hour. Air at the rate of 90 standard cubic feet per hour is then injected into the charge. After thorough mixing, catalyst in the form of doctor solution of a concentration of 15.6 grams PbO per liter of solution is injected at a rate of 1.4 gallons per hour. The intermixed naphtha, caustic, inhibitor, and metal catalyst are introduced into an isolated time tank and allowed to stand. Tests on samples taken just before the treated naphtha enters the time tank, and at various periods after entering the tank, are set forth in Table M.

Table M

Data Collected	Standing Interval in Time Tank				
	1 Hour	2 Days	3 Days	5 Days	9 Days
Doctor Test.....	Pos. 0.61	Neg. 0.27	Neg. 0.34	Neg. 4	Neg. 0.16
Peroxide Number.....	15	14	7	4	2
Blended Copper Dish Gum.....					

In conducting the process according to the invention it has been determined that the metal catalyst is capable, in some way, of altering the recycled caustic so that it continues to achieve the catalytic effect even though the injection of catalyst is discontinued. This phenomenon is not clearly understood, particularly since, on analysis, no metal has been found in the recycled caustic. The following examples, with particular reference to prior Examples 7 to 9, illustrate the effects subsequent to discontinuing the injection of catalyst.

EXAMPLE 12

Operations are conducted as described in Example 7

13

for a period of 12 days, after which time the injection of doctor solution is discontinued while maintaining the other conditions constant. Fifteen minutes thereafter samples of naphtha are taken at the entrance to the time tank, and tested. Tests, repeated at intervals, on the samples so taken are shown in Table N.

Table N

Data Collected	At Entrance to Time Tank	After 2 Days Standing	After 7 Days Standing
Grams Mercaptans S per 100 cc. of naphtha.	0.00083	Less than 0.0002	Less than 0.0002
Peroxide Number	0.54	0.43	0.23
Blended Copper Dish Gum	6	28	8
ASTM Gum	0.2	0.2	0.0

EXAMPLE 13

Operations are conducted as described in Example 8 for a period of 2 days. The injection of doctor solution is then discontinued while maintaining the other conditions constant. Two hours thereafter samples are taken and tested as set forth below:

Table O

Data Collected	At Entrance to Time Tank	After 1 Day Standing	After 2 Days Standing
Grams Mercaptans S per 100 cc. of naphtha.	0.00140	0.00070	Less than 0.00020
Peroxide Number	0.71	0.35	0.08
Blended Copper Dish Gum	4	7	0
ASTM Gum	0.2	0.2	0.0

EXAMPLE 14

The injection of doctor solution, described in Example 9, is discontinued after 5 days, all other conditions remaining constant. Two and one-half hours later samples are taken and tested as shown in Table P.

Table P

Data Collected	At Entrance to Time Tank	After 1 Day in Time Tank	After 2 Days in Time Tank
Grams Mercaptans S per 100 cc. of naphtha.	0.0013	0.00070	Less than 0.00020
Peroxide Number	0.63	0.30	0.08
Blended Copper Dish Gum	8	10	2

A comparison of data, as for example in Tables K and P, indicates that a substantial reduction in peroxide and gum formation within the naphtha can be achieved at intervals of at least 2½ hours after the injection of catalyst is discontinued.

A further advantage of the metal catalyst resides in its power to effect a regeneration of the mercaptan extractive powers of the aqueous caustic during the period of contact with the naphtha. This effect is illustrated in the following example.

EXAMPLE 15

Prior to any injection of catalyst, a catalytically cracked naphtha, from the cracking of a mixture of gas oils derived primarily from California and Middle East crudes with a boiling range of 106° F. to 266° F., and having a mercaptan content (as sulfur) of 0.006 gram per 100 cc. of stock is processed substantially as in the drawing. As in Example 8, the sour naphtha is charged at a rate of 250 barrels per hour, injected with 1.9 pounds per hour of NN' disecbutyl paraphenylen diamine inhibitor, mixed with 60 barrels of a 4.5 percent solution of aqueous caustic soda solution per hour, and injected with air at the rate of 90 standard cubic feet per hour. Subsequently, the entire process is repeated exactly as in the drawing with doctor solution of a concentration of 14.3 grams

14

PbO per liter of solution also being injected at a rate of 1.4 gallons per hour (0.00021 percent Pb by weight). In each case, samples of caustic are taken just before the intermixed caustic and naphtha enters the time tank, and one day after entering the tank.

Table Q

Data Collected	No Metal Injected		Doctor Solution Injected	
	At Entrance To Time Tank	After 1 day In Time Tank	At Entrance To Time Tank	After 1 day In Time Tank
Grams mercaptan S per 100 cc. of caustic.	0.08	0.06	0.04	0.007

The above results were verified in additional tests in which the addition of the catalyst metal was found to reduce the mercaptan sulfur in the caustic from about 0.07 to 0.10 gram at the entrance to the tank to about 0.02 to 0.05 gram, and after one day in the tank from about 0.5 to 0.8 gram to about 0.005 to 0.01 gram.

The second-mentioned form of the invention has important advantages.

Contrary to the conventional use of doctor solution to sweeten gasoline, where a large excess of doctor solution is required to react with the mercaptans to form mercaptides and the mercaptides in turn are reacted with elemental sulfur to produce disulfides, the present invention uses only catalytic amounts of doctor solution (i. e., less than the stoichiometric amounts of sodium plumbite are used.)

The amount of the two inhibitors will vary but, in general, the hindered phenol is added at the rate of 2.5 to 5 lbs. of 1000 bbls. of naphtha and the phenylene diamine is added at the rate of 5 to 10 lbs. per 1000 bbls. though more may be used if desired.

The following examples illustrate, according to the general procedure outlined in the drawing, the effect of using hindered phenol in conjunction with a phenylene diamine inhibitor compared to similar processing without the hindered phenol.

EXAMPLE 16

A catalytically cracked naphtha, from the cracking of a mixture of gas oils derived primarily from California and Middle East crudes with a boiling range of 110° F. to 200° F., and having a mercaptan content (as sulfur) of 0.0055 gram per 100 cc. of stock is processed as in the drawing. The sour naphtha is charged at a rate of 250 barrels per hour and injected with 2.5 pounds per hour of NN' disecbutyl paraphenylen diamine inhibitor. A 40 percent solution of aqueous caustic soda from the time tank is recycled with the charge at 50 barrels per hour. Air at the rate of 90 standard cubic feet per hour is then injected into the charge. After thorough mixing, catalyst in the form of doctor solution of a concentration of 11.1 grams PbO per liter of solution is injected at a rate of 1.0 gallons per hour (0.000162 percent Pb by weight). Tests on samples taken just before the treated naphtha enters the time tank, and at various periods after entering the tank, are set forth in Table R.

65

Table R

Data Collected	At Entrance To Time Tank	After 2 days in Time Tank	After 8 days in Time Tank
Grams mercaptans S per 100 cc. of naphtha.	0.0012	0.00020	Less than 0.0002
Peroxide Number	0.52	0.25	0.18
Blended Copper Dish Gum	22	15	13
ASTM Gum	0.2	0.0	0.0

75

EXAMPLE 17

A catalytically cracked naphtha similar to that in Example 16 but having an initial mercaptan content (as sulfur of 0.0060 gram per 100 cc. of naphtha) is processed in the same manner as in Example 16, except the gasoline is injected with 1.25 pounds per hour of 2,6-ditertiary butyl para cresol in addition to 2.5 pounds per hour of phenylene diamine inhibitor, and a 4.5 percent solution of caustic soda is employed. Samples are withdrawn from the time tank and tested as shown in Table S.

Table S

Data Collected	At Entrance To Time Tank	After 2 days in Time Tank	After 6 days in Time Tank
Grams Mercaptans S per 100 cc. of naphtha.....	0.0024	0.00028	Less than 0.00020
Peroxide Number.....	0.15	0.07	0.06
Blended Copper Dish Gum.....	7	3	0
ASTM Gum.....	0.4	0.2	0.2

EXAMPLE 18

The procedure of Example 16 is repeated with heavy thermally cracked naphtha having an initial mercaptan content (as sulfur) of 0.00092 gram per 100 cc. of naphtha and a boiling range of 205° to 395° F. The sour naphtha is charged at the rate of 175 barrels per hour and 5% by volume of butane is injected to raise the vapor pressure. NN' dissecondary butyl para phenylene diamine inhibitor is then injected at the rate of 1.5 pounds per hour. A 4.5 percent solution of aqueous caustic soda from the time tank is recycled with the charge at 40 barrels per hour. Air at the rate of 40 standard cubic feet per hour and catalyst in the form of doctor solution of a concentration of 18.1 gms. of PbO per liter is injected at a rate of 1 gallon per hour. Tests on samples taken just before and at various periods after the naphtha entered the time tank produce the following results:

Table T

Data Collected	At Entrance To Time Tank	After 2 days in Time Tank	After 4 days in Time Tank
Grams Mercaptans S per 100 cc. of naphtha.....	0.00068	0.00035	0.00020
Peroxide Number.....	3.5	3.1	2.8
Blended Copper Dish Gum.....	162	172	175

The results of Example 18 show that sweetening of heavy thermal naphtha inhibited with only phenylene diamine inhibitor leads to unsatisfactory product quality.

EXAMPLE 19

The procedure of Example 18 is repeated with heavy thermally cracked naphtha similar to that in Example 18, except that the gasoline having an initial mercaptan sulfur content of 0.0011 gm. per 100 cc. is further inhibited, before contact with air or caustic, with 0.8 pound per hour of 2,6-ditertiary butyl para cresol. Results obtained in the time tank are shown in Table U.

Table U

Data Collected	At Entrance To Time Tank	After 2 days in Time Tank	After 4 days in Time Tank
Grams Mercaptans S per 100 cc. of naphtha.....	0.00070	0.00046	0.00027
Peroxide Number.....	0.58	0.47	0.40
Blended Copper Dish Gum.....	43	40	37

EXAMPLE 20

The procedure of Example 19 is repeated on heavy thermally cracked naphtha, having an initial mercaptan content of 0.00095 except that a stream of gasoline is con-

tinuously withdrawn from the time tank and injected into line 4 previous to the injection of doctor solution at the rate of 50 barrels per hour. Results obtained in the time tank are shown in Table V.

Table V

	Data Collected	At Entrance To Time Tank	After 2 days in Time Tank	After 4 days in Time Tank
10	Grams Mercaptans S per 100 cc. of naphtha.....		0.00040	0.00023
15	Peroxide Number.....	0.31 22	0.23 15	0.18 10

These results indicate clearly that recirculation of part of the gasoline in the time tank accelerates sweetening and leads to improved product quality.

To those skilled in the art of which this invention relates, it will be clear that the invention makes possible a rapid, efficient sweetening of gasolines, using a modified "inhibitor sweetening" procedure with greatly reduced by-product formation of organic peroxides thereby resulting in decreased gum formation and cleaner engines. The invention also makes possible the regeneration of caustic wash solutions, in situ, without the necessity of expensive or involved regeneration procedures. However, it will be understood that the disclosures and the descriptions herein, such as those relating to the destruction of peroxides formed during inhibitor sweetening, are purely illustrative and are not intended to be in any sense limiting. Thus, organic peroxides necessary to the efficient performance of the disclosed process could be supplied independently of inhibitor sweetening processes, as (for example) by a direct addition of peroxides to the caustic recirculation line 14 through valve 19. Thus, the injection of the catalyst may occur at other points in the system, such as prior to mixing tank 8 or mixing tank 8 could be eliminated, without appreciably varying the success achieved by the new process.

Similarly, the point of injection of the air, or other oxygen-containing gas, may be varied and may be either before, simultaneously or after the catalyst injection. Accordingly, all such changes in construction or variations and applications of the invention, which would naturally suggest themselves to a worker in the art are considered within the spirit and scope of the invention.

I claim:

1. The process of simultaneously sweetening and reducing the content of gum-producing peroxides in a sour hydrocarbon oil which comprises reacting mercaptans and organic peroxides contained in the oil in the presence of an aqueous alkaline solution containing in the form of a salt a catalytic amount less than about 0.003% by weight of a metal selected from the group consisting of lead, bismuth, and thallium.
2. The process of claim 1 in which said peroxides are formed in said hydrocarbon oil by contacting the oil with air in the presence of a phenylene diamine type inhibitor and a hindered phenol type of inhibitor.
3. The process of claim 2 in which the hindered phenol type inhibitor is a member of the group consisting of 2,6-ditertiary butyl para cresol and 2,6-ditertiary butyl phenol.
4. The process of claim 2 in which the phenylene diamine type inhibitor is added to the oil at a rate in the order of 5 to 10 pounds per 1000 barrels and the hindered phenol type of inhibitor is added to the oil at a rate in the order of 2.5 to 5 pounds per 1000 barrels.
5. The process of claim 1 in which said peroxides are formed in said hydrocarbon oil by contacting the oil with air in the presence of a phenylene diamine type inhibitor.

17

6. The process of claim 1 in which said peroxides are added to said oil from an extraneous source.

7. The process of claim 1 in which said hydrocarbon oil is a cracked naphtha.

8. In a process of sweetening light petroleum hydrocarbon oils of a type suitable for motor fuels in which a small amount of an oil-soluble phenylene diamine inhibitor is dissolved in said oil, the step of contacting the oil with an aqueous alkaline solution containing in the form of a salt a catalytic amount less than about 0.003% by weight of metal selected from the group consisting of lead, bismuth and thallium.

9. The process of claim 8 in which said metal is present in the alkaline solution in the form of sodium plumbite.

10. A process of sweetening sour hydrocarbon oils, containing objectionable amounts of mercaptans, which comprises contacting the oil containing a phenylene diamine type inhibitor with aqueous caustic containing a small amount less than 0.003% by weight of a catalyst in the presence of air, said catalyst being a metal in soluble form selected from the group consisting of lead, bismuth and thallium.

11. The process of claim 10 in which said metal catalyst is present in the aqueous caustic in an amount between about 0.00005 parts and 0.001 parts metal per 100 parts of hydrocarbon oil.

12. The process of claim 1 in which said metal catalyst is lead, added in the form of doctor solution.

13. In the process of sweetening hydrocarbon oils which have been treated by conventional sweetening processes tending to produce gum-forming peroxides and which still contain small but objectionable amounts of mercaptans the finishing step which includes contacting the oil with an aqueous caustic solution of a metal catalyst selected from the group consisting of lead, bismuth and thallium for a reaction between said peroxides and mercaptans which has the properties of easily undergoing oxidation-reduction reactions and of readily forming mercaptides on contact with mercaptans, the catalyst being present in an amount at least 0.00005% and less than about 0.003% by weight.

14. In combination with a process wherein a stream of sour cracked hydrocarbon oil is contacted with a stream of caustic soda solution and the resulting mixture is permitted to settle, the resulting phases remain in contact in the presence of oxygen dissolved in the oil under conditions which result in the simultaneous formation of peroxides in the oil and conversion of mercaptans to disulfides, and a stream of the separated caustic soda phase is recycled to contact further quantities of oil, the method of increasing the rate of formation of disulfides and decreasing the final peroxide content of the oil, which comprises adding doctor solution to the caustic soda stream in an amount sufficient to increase the rate of formation of said disulfides but not substantially more than a rate of about 0.003 parts by weight of lead per 100 parts hydrocarbon oil.

15. The method of claim 14 wherein the oil contains a phenylene diamine type inhibitor effective to promote the formation of disulfides.

16. The method of claim 14 wherein the oil contains both a phenylene diamine type inhibitor and a hindered phenol type inhibitor.

17. In a process of sweetening light petroleum hydrocarbon oils of a type suitable for motor fuels in which

18

a small amount of an oil-soluble phenylene diamine inhibitor and a small amount of an oil-soluble hindered phenol inhibitor are dissolved in said oil, the step of contacting the oil with an aqueous alkaline solution containing in the form of a salt a catalytic amount less than about 0.003% by weight of metal selected from the group consisting of lead, bismuth and thallium.

18. A process of sweetening sour hydrocarbon oils, containing objectionable amounts of mercaptans, which comprises contacting the oil containing a phenylene diamine type inhibitor and a hindered phenol type inhibitor with aqueous caustic containing a small amount less than 0.003% by weight of a catalyst in the presence of air, said catalyst being a metal in soluble form selected from the group consisting of lead, bismuth and thallium.

19. In combination with a process wherein a stream of sour cracked hydrocarbon oil is contacted with a stream of caustic soda solution and the resulting mixture is permitted to settle, the resulting phases remain in contact in the presence of oxygen dissolved in the oil under conditions which result in the simultaneous formation of peroxides in the oil and conversion of mercaptans to disulfides, and a stream of the separated caustic soda phase is recycled to contact further quantities of oil, the method of increasing the rate of formation of disulfides and decreasing the final peroxide content of the oil, which comprises: adding doctor solution to the caustic soda stream in an amount sufficient to increase the rate of formation of said disulfides but not substantially more than a rate of about 0.003 parts by weight of lead per 100 parts hydrocarbon oil, adding to the oil a phenylene diamine type inhibitor in an amount effective to promote the formation of disulfides, and adding to the oil a hindered phenol type of inhibitor in an amount sufficient to substantially suppress the formation of peroxides.

20. The method of claim 19 in which the hydrocarbon oil phase is maintained in motion while it remains in contact with the caustic soda phase, by transferring oil phase from one locus to a second locus in a time tank.

21. The process of claim 19 in which the hindered phenol type inhibitor is a member of the group consisting of 2,6-ditertiary butyl para cresol and 2,6-ditertiary butyl phenol.

22. The process of claim 19 in which the phenylene diamine type inhibitor is added to the oil at a rate in the order of 5 to 10 pounds per 1000 barrels.

23. The process of claim 19 in which the hindered phenol type inhibitor is added to the oil at a rate in the order of 2.5 to 5 pounds per 1000 barrels.
